UNITED STATES PATENT OFFICE.

JOSEPH S. WIGGINS, OF HAWORTH, NEW JERSEY.

CIRCUIT-CONTROLLER ATTACHMENT FOR CLOCKS.

Application filed March 10, 1924. Serial No. 697,993.

To all whom it may concern:

Be it known that I, JOSEPH S. WIGGINS, a citizen of the United States, residing at Haworth, in the county of Bergen and State of New Jersey, have invented certain new and useful Improvements in Circuit-Controller Attachments for Clocks, of which the following is a specification.

This invention relates generally to a circuit controlling attachment for clocks and more particularly to a device of this general nature adapted for use with clocks installed in motor vehicles for automatically turning on the lights of the vehicle at a pre-determined hour.

The invention includes a switch operating arm arranged to be mounted on the winding shaft of an alarm mechanism with which the clock may be provided together with means available from a point adjacent the face of the clock for rotating the shaft to swing the arm to withdrawn position so that when the alarm mechanism is released at the predetermined hour the shaft is rotated to its initial position and swings the arm into operative or circuit closing position.

The invention also includes the provision of means for holding the switch arm in its withdrawn or inoperative position until such time as it may be placed in condition by the operator to be released at a subsequent hour selected by the operator and at which the mechanism is set to operate.

The invention also includes means convenient to the operator and adjacent the face of the clock for setting the mechanism to operate at the desired subsequent time.

By the use of the described mechanism the operator may so set the mechanism during daylight hours that a switch will be automatically closed at a predetermined hour in the evening to turn on the parking lights of the vehicle. The turning off of the lights at a later hour is utilized to prevent the automatic switching on of the lights at the hour in the morning corresponding to the lighting hour in the evening, the referred to act of the operator during daylight hours serving to place the mechanism in condition to close the circuit at the predetermined evening hour.

In the drawings,

Figure 1 is a face view of a motor vehicle clock equipped with a switch operating device embodying the invention.

Figure 2 is a rear view of the clock shown in Figure 1.

Figure 3 is a view in side elevation and partly in section of the device shown in Figure 1.

Figure 4 is a side view of a device for setting operating mechanism forming part of the clock shown in Figure 1.

Figure 5 is a plan view of switch operating parts embodying the invention and with the parts shown in switch closing position.

Figure 6 is a view similar to Figure 5 showing the parts in inoperative position and held in that position.

Figure 7 is a view similar to Figure 6 showing the switch arm in open position and ready for automatic release to swing to closed position.

Figure 8 is a view in perspective of a switch operating attachment.

Figure 9 is a sectional view on an enlarged scale of the switch operating parts shown in Figure 6.

Figure 10 is a view in perspective of a switch operating arm forming part of the switch operating device.

Figure 11 is a view of the switch parts shown in open position.

Referring to the drawings for a more detailed description of the invention, a clock 10 is shown which is preferably of the general type adapted to be mounted on the switch or control board 10' facing the position of the driver of a motor vehicle. The clock may be provided with any standard type of works 11 mounted in a casing 12 which is adapted to be fitted into an opening prepared for the purpose in the board or panel 10'. The driving spring of the works 11 or train may be wound in any suitable manner by means not disclosed herein since this feature has no particular bearing on the invention herein described.

As has already been pointed out a principal feature of the present invention is to provide an attachment for a clock of any general nature and particularly for the type of clock adapted for use with motor vehicles, which will adapt the clock to control an electrical circuit for any desired purpose such as to turn on the parking lights of the vehicle on which the clock is mounted. The attachment by which this useful function is attained includes a supporting frame member 13 which can be conveniently attached to the main frame members 11' of the clock.

work. The frame member 13 is provided with a circuit closing arm 14 which is mounted on the end of the shaft which is used to wind the alarm operating mechanism in an ordinary clock of the alarm type, the clock to which the control device herein described is attached being provided with the alarm gear train for the purpose of this invention. In order to cause the arm 14 to be used to rotate the gear train winding shaft 15 the knurled thumb piece which is ordinarily attached to the shaft 15 is removed and the arm 14 is substituted therefor, the arm having a threaded connection with the end of the shaft 15 and being provided with an upstanding circular lug 17 to form a bearing or axis on which a setting arm 20 may rotate, the arm 20 being held in position on the lug by means of a nut or holding member 18 which has threaded engagement with the upper end of the shaft 15. The setting arm 20 has a link connection 21 with an arm 22 carried by the end of a regulating rod 23 terminating in a wing nut 24 located adjacent the dial of the clock adjacent the margin thereof in a position accessible to the operator or driver of the vehicle. The setting arm 20 has a one-way operating connection with the circuit control arm 14 through the engagement of the arm 20 with an upstanding lug 25 carried by a rearward extension of the switch or circuit closing arm 14 as is clearly shown in Figure 8 of the drawing.

35 The outer extremity of the circuit closing arm 14 is provided with a roller 26 formed of fiber or other insulating material and which is adapted to engage a spring terminal member 27 of a circuit closer 28 to thereby force the spring terminal 27 into engagement with the other terminal 29 of the circuit closer to thereby close a circuit through the conductors 30 leading, for example, to the lighting system of the car.

40 45 In the operation of the device the wing nut 24 is turned to swing the setting arm 20 into the position shown in Figure 6 of the drawings in which the circuit controlling arm 14 is swung to a position substantially ninety degrees from the position in which the arm is in circuit closing position as in Figure 5 of the drawing. If the inoperative position of the arm 14 thus described is established, for instance during daylight hours, the wing nut is then turned in a reverse direction to return the setting arm 20 to a horizontal position such as is shown in Figure 7 of the drawing, leaving however the circuit controlling arm 14 in its relatively vertical position. This position of the arm 14 is maintained through the functioning of a ratchet and pawl device in the alarm setting gear mechanism, which includes the shaft 15 on which the arm 14 is carried for rotation therewith.

With the relative position of the parts established as in Figure 7 of the drawing when the predetermined time has arrived for the closing of the circuit controller 28, the alarm gear train acts to release the shaft 15 for rotation whereupon the spring included in the alarm operating mechanism returns the shaft 15 to its initial position thereby swinging the arm 14 into position shown in Figure 5 of the drawing in which the roller 26 engages and forces a spring terminal 27 into contact with the terminal 29 to thereby close the desired circuit.

In the normal operation of the device the closing of the switch would naturally be caused to take place during the daylight hours in order to turn on a parking lamp automatically in the absence of the driver of the vehicle. Later in the evening when it is desired to turn off the lights the operator turns the wing nut 24 to swing the parts to the position shown in Figure 6 of the drawing and allows both the circuit controlling arm 14 and the setting arm 20 to remain in this inoperative position. The reason for this is that when the next morning hour on the clock arrives which corresponds to the hour in the evening at which it is desired to utilize the device, it is necessary to cause the parts to remain inoperative. This is accomplished by leaving the parts in the position shown in Figure 6 in which it will be seen that the link member 21 is so formed as to bring an inwardly curved part 31 thereon into abutting engagement with a stop member 32 projecting upwardly from the end of the arm 22 in alignment with the regulating stem or shaft 23. By this arrangement the parts remain in interlocked position, a dead center effect being established between the extremities of the curved link member 21 and the stop member 32 therebetween.

It will be seen that when the morning hour is passed which corresponds to the control hour at the other end of the day it is necessary merely for the operator to reverse the direction of rotation of the wing nut 24 and again bring the parts into the position shown in Figure 7 of the drawing which has already been described whereupon when the predetermined hour has arrived at the close of the day the parts will again automatically operate to close the circuit as described. In order to provide means for setting the alarm regulated gear which is utilized in the operation of the herein described invention, the thumb nut which is ordinarily employed at the back of the clock on the alarm setting shaft 33 is removed and replaced by a spur gear 34. In order to rotate the gear 34 and thereby set the alarm gear train a U-shaped frame member 35 is formed to be attached to the main frame members 11 of the clock work in much the same manner that the frame member 13 is attached thereto. The

frame piece 35 forms a bearing support for a shaft 36 which carries at its inner end a spur gear 40 meshing with the spur 34 on the shaft 33 and carries at its outer end a 5 knurled thumb piece 37 through the operation of which the pointer 38 can be moved to the hour indicated on the dial 39 at which it is desired to have the switch operating mechanism act to close the contacts 27 and 10 29 to thereby close the appropriate circuit.

It will be seen that a simple and efficient device for the purpose has been devised which can be readily attached to existing and standard forms of motor vehicle as well 15 as other clocks to bring about the operation of a circuit controller for lighting the lamps on the vehicle at a predetermined evening hour or for any other appropriate or desired purpose. The placing of the controls 24 and 20 37 for the device in a position conveniently reached by and accessible to the operator overcomes the necessity for removing the clock from its seat to set or adjust the mechanism so that the automatic turning on of 25 the vehicle lights at a desired hour can be readily accomplished.

What I claim is:—

1. In a circuit controller attachment for a clock fitted with an operating mechanism 30 adapted to be released for actuation at a predetermined hour, a circuit closer, an arm mounted on the winding stem of the mechanism and arranged to operate the circuit closer when the mechanism is released for 35 actuation, a setting arm mounted to freely turn on the winding stem and having a one-way connection with the operating arm whereby to turn the operating arm and winding stem to set position, said setting arm being movable to a position to permit the operating arm to swing to circuit controlling position when the winding stem is 40 released, and actuating means for the setting arm accessible at the face of the clock.
2. In a circuit controller attachment for a clock fitted with an operating mechanism, a circuit closer, an arm mounted on the winding stem of the mechanism and arranged to operate the circuit closer when the mechanism is released for actuation, a setting arm mounted to freely turn on the winding stem and arranged to engage the operating arm to move the shaft to set position, said setting arm being adapted to be left in position to 45 hold the shaft in inoperative position or to be withdrawn to permit the shaft to operate when subsequently released said arms being located at the back of the clock.
3. In a circuit controller attachment for 50 motor vehicle clocks of the type adapted to be seated in an opening in the vehicle instrument board, said clock including a mechanism adapted to be released for actuation at a predetermined hour, an arm mounted on the winding stem of the mechanism at the 55 back of the clock, a circuit controller arranged to be operated by the arm when the stem is released for operation, a setting arm mounted to freely turn on the winding stem and arranged to engage the operating arm 60 to move the shaft to set position, a setting shaft adjacent the winding shaft, a crank arm carried by the shaft to turn therewith, and a link connecting the crank arm on the setting shaft with the setting arm whereby 65 to actuate the same.
4. In a circuit controller attachment for 70 motor vehicle clocks of the type adapted to be seated in an opening in the vehicle instrument board, said clock including a mechanism adapted to be released for actuation at a predetermined hour, an arm mounted on the winding stem of the mechanism at the back of the clock, a circuit controller arranged to be operated by the arm when the stem is released for operation, a setting arm mounted to freely turn on the winding stem, 75 a lug on the operating arm adapted to be engaged by the setting arm in one direction of movement, a setting shaft extending from the face of the clock to a position adjacent 80 the setting arm, a crank arm on the setting shaft, and a bowed link connecting the crank arm and the setting arm, whereby rotation of the setting shaft in one direction will set the operating arm and lock the parts in inoperative position through a locked-on-center disposition of the bowed link with 85 relation to the projecting end of the setting shaft and rotation of the setting shaft in the opposite direction will permit the operating arm to move when the winding shaft is released.
5. In a circuit controller attachment for 90 motor vehicle clocks, a U-shaped frame member adapted to be attached to the spaced apart frame pieces of the clock works, a shaft journaled in said frame member and terminating in a hand turning member adjacent the face of the clock, a circuit controller actuating arm mounted on the winding stem of operating mechanism included in the clock and arranged to actuate the circuit controller when the shaft is released for 95 rotation by the mechanism, an outwardly extending lug carried by said arm, a second arm on the shaft rotatable relatively thereto and arranged to engage said lug to thereby 100 swing the first-named arm and stem to inoperative position and wind the mechanism, a crank on the shaft, and a link connection between the crank and second-named arm, said link being bowed to engage a stop at the end of the shaft to thereby lock the parts in inoperative position.
6. In a circuit controller attachment for 105 motor vehicle clocks, a U-shaped frame member adapted to be attached to the spaced apart frame pieces of the clock works, a shaft journaled in said frame member and termi- 110

nating in a hand turning member adjacent the face of the clock, a circuit controller actuating arm mounted on the winding stem of operating mechanism included in the 5 clock and arranged to operate when the shaft is released for rotation by the mechanism, an operating connection between the inner end of the shaft journaled in the frame

member and the winding stem for setting the controller actuating arm and the winding stem, and said operating connection being adapted to hold the actuating arm in inoperative position or to be withdrawn to permit the arm to operate when released by the clock mechanism. 10

JOSEPH S. WIGGINS.
